ANIMAL MARKING TAG

Leo M. McCarty, 2583 S. Dexter, Denver, Colo. 80222

Filed Aug. 26, 1970, Ser. No. 24,713

Term of patent 14 years

Int. Cl. D30—99

U.S. Cl. D30—43

FIG. 1 is a perspective view of the animal marking tag showing my new design;

FIG. 2 is a bottom plan view thereof;

FIG. 3 is a side view thereof;

FIG. 4 is a top plan view thereof;

FIG. 5 is a right end view thereof as viewed in FIG. 1, and

FIG. 6 is a left end view thereof as viewed in FIG. 1. I claim:

The ornamental design for an animal marking tag, as shown.
